UNITED STATES PATENT OFFICE

108,094

DESIGN FOR A COMBINED BEVERAGE COOLER AND DISPENSER

Fred G. Wilson, Brooklyn, N. Y.

Application April 30, 1937, Serial No. 69,086

Term of patent 14 years

To all whom it may concern:

Be it known that I, Fred G. Wilson, a citizen of the United States, residing at Brooklyn, in the county of Kings and State of New York, have invented a new, original, and ornamental Design for a Combined Beverage Cooler and Dispenser, of which the following is a specification, reference being had to the accompanying drawing, forming part thereof.

The figure is a perspective view of a combined beverage cooler and dispenser showing my new design.

I claim:

The ornamental design for a combined beverage cooler and dispenser, as shown.

FRED G. WILSON.
